US00D887769S

(12) **United States Design Patent** (10) Patent No.: **US D887,769 S**
(45) Date of Patent: **** Jun. 23, 2020**

(54) **ADDITIVE VESSEL**(71) Applicant: **LifeFuels, Inc.**, Reston, VA (US)(72) Inventors: **Mark Lyons**, Reston, VA (US); **Robert Lawson-Shanks**, Reston, VA (US); **Jonathon Perrelli**, Reston, VA (US); **Justin Toelle**, Reston, VA (US); **Benjamin Gillette**, Reston, VA (US); **Simon Lewis Bilton**, Reston, VA (US); **Adam Harvey-Cook**, Reston, VA (US); **Matthew James Edwards**, Reston, VA (US)(73) Assignee: **LifeFuels, Inc.**, Reston, VA (US)(***) Term: **15 Years**(21) Appl. No.: **29/632,269**(22) Filed: **Jan. 5, 2018**(51) LOC (12) Cl. **31-00**

(57) **CLAIM**

The ornamental design for an additive vessel, as shown and described.

DESCRIPTION

FIG. 1 is a front perspective view of an additive vessel showing the new design;

FIG. 2 is a bottom perspective view thereof;

FIG. 3 is a front view thereof;

FIG. 4 is a rear view thereof;

FIG. 5 is a right view thereof;

FIG. 6 is a left view thereof;

FIG. 7 is a top view thereof; and,

FIG. 8 is a bottom view thereof.

1 Claim, 8 Drawing Sheets
